[57] ABSTRACT

A device facilitates the saddling of a horse and makes it more flexible insofar as the fastening between the rigging ring positioned on the saddle and the cinch or cinch strap which engages the under belly of the horse is concerned. A rotary winch equipped with protruding teeth is positioned in a suitable housing holding a belt, one end of which passes through the rigging ring and the other end is permanently fastened to the housing. The protruding teeth in the winch roller engage holes positioned along the length of the belt. A suitable wrench permits rotating of the roller or winch thereby effecting tightening of the belt which may be held in any given position or released therefrom by a suitable latch and release mechanism.

FIG. 1.

FIG. 2.

SHEET 2 OF 2

FIG. 3.

FIG. 3A

CINCH WINCH FOR SADDLING A HORSE

BACKGROUND OF THE INVENTION

For generations one of the important steps in saddling of a horse comprised the operation of fastening of the saddle to the horse through a cinch strap engaging the horse's under belly by means of an additional leather strap known as the latigo strap which was tied to the saddle rigging ring and then threaded through the cinch ring a couple of times. After this a latigo knot was made. This strap engaged a ring known as a cinch ring which was connected to and formed a part of the cinch or cinch strap passing under the belly of the horse. The other end of the strap passed through a ring which was fixedly positioned on the saddle and made secure by means of a knot tied in the strap which was known as a latigo knot. In the usual saddle arrangement this knot was located under the stirrup leather where it was rather bulky and sometimes interfered with the stirrup itself. In any event, it was a cumbersome operation to tie this knot and did not permit any flexibility once it was tied and while the rider was on the horse.

Applicant is not aware at this time of any device or other means of performing this operation and saddling a horse other than the one described above which has been used from time immemorial.

SUMMARY OF THE INVENTION

I have discovered that by use of the device of my invention I am able to overcome all the disadvantages of the old method of saddling.

I provide a housing in which is located a roller or rotating winch, the housing being adapted for positioning against the side of the horse's body. On the lower end of the housing I provide a hook which engages the conventional cinch ring which in turn is permanently connected to the strap passing under the horse's belly. At the upper end of my housing I provide means for permanently fastening one end of a strap. I then pass my strap through a more or less conventional saddle ring located on the saddle itself, double it back and then pass it back down to the housing again where it is disposed to engage my winch or roller. The strap is equipped with suitably spaced holes along its entire length which are in turn disposed to engage protruding teeth in the roller, means being provided to guide the strap over the roller to insure positive engagement between the strap and the roller teeth. I provide a portable wrench which may be of the socket or other type to permit rotating of the roller and causing the teeth to tighten or loosen my strap. A novel dog or latch arrangement is positioned to engage the teeth and hold them in any given position as desired. A release mechanism is positioned in the housing to release my dog or latch at any time it is so desired and permit adjusting the strap and consequently the entire saddle assembly in a tighter or looser relationship with the horse as is desired.

My combination makes the saddling assembly stronger and more secure. It may be tightened and fastened while the person is mounted and is especially convenient for young riders, as well as the old and handicapped, to tighten and maintain a desired tension adding greatly to the safety of the saddle. It likewise eliminates the bulky latigo knot under the stirrup leather and is easy to change from one saddle to another. Be-

cause of its simplicity and flexibility it will outlast several latigos, making it cheaper in the long run.

Of particular advantage is the feature which permits changing the amount of tension on the horse while riding, since it is well known to experienced riders that the horse may expand or contract its muscles depending on the riding, strain, temperature, and so on, all of which may be compensated for while the rider is mounted and without dismounting and retying the latigo knot.

DESCRIPTION OF THE DRAWINGS

FIG. 1 is a general assembly showing the position and relationship of my device to a horse and saddle.

FIG. 2 is a cross-section along the lines 2-2 of FIG. 15 3 showing the internal arrangement of the mechanism of my invention.

FIG. 3 is a perspective showing the general assembly of my invention with all the component parts.

FIG. 3A shows one type of wrench which may be 20 used with my invention.

DESCRIPTION OF A PREFERRED EMBODIMENT

Referring now to the drawings and particularly first to FIG. 1 there is shown first a horse 1 and a saddle 2 which may be of any type in common use. The saddle is equipped with stirrups 3 and has positioned upon it saddle ring 4.

My strap or belt 5 has one end fixedly positioned on housing 6 and the other end passing through saddle ring 30 4 and returning back through housing 6 where it engages my winch mechanism as described below and then passes out through the housing and has a loose end as shown.

Cinch ring 9 engages strap 10 which is a conventional 35 cinch strap which passes under the belly of the horse. Cinch ring 9 also engages the bottom end of my housing 6 through a permanent hook and spring arrangement as described more fully below.

Seen better now on FIG. 3 is my housing 6 which has positioned upon it and in rotating relation with it my winch 7. A hook 8 which forms an integral part of my housing 6 is disposed to engage saddle ring 9 as described more fully below.

Referring again more particularly now to FIG. 3, my 45 strap 5 is seen to pass under pin 21 located in housing 6 and thence to engage the teeth 22 in my roller or winch 7. The socket 23 is provided to permit engagement by a suitable wrench shown in perspective in FIG. 3A to permit rotation of drum 7 as needed and which may be located in a saddle bag or suitable receptacle for convenient access by the rider.

My strap or belt 5 is equipped with holes or perforations 24 positioned along its length and disposed to engage with the teeth 22 of roller 7. After passing through teeth 22 my strap 5 hangs loosely below housing 6 as shown at 25.

To insure the retention of my cinch ring 9 inside of hook 8 I may employ a spring 26 which may be of a conventional leaf type easily released and snapped into 60 position.

The relationships between the components of my mechanism may be understood better by reference to FIG. 2 as well as FIG. 3. To maintain the roller 7 in any given position and consequently any degree of tension in belt 5 I utilize a dog or latch 27 mounted on a pin 28. This is disposed to engage the teeth 22 when in a horizontal position but may be disengaged by movement of

release 29 to a lower position permitting free rotation of roller 7. My roller dog or latch 27 may be spring activated, thereby maintaining constant tension against latch release 29.

I enclose my housing 6 with an easily removable cover plate 30, having holes 31 adapted for mating with holes 32 in my housing 6 and being held in position by a pin 33.

OPERATION

The operation of my device should now be evident to those skilled in the art but a brief description for purposes of clarification follows.

After the saddle 2 is placed on the horse 1, I bring my device into position by engaging hook 8 with cinch ring 9 and passing my strap or belt 5 through saddle ring 4 and thence downward back into housing 6 underneath pin 21 and around roller 7 engaging holes 24 with teeth 22. At this point roller dog or latch 27 engages teeth 22 as shown. This operation is performed only once unless 20 cinch winch is to be used on another saddle.

By means of the wrench shown on FIG. 3A I may rotate roller 7 and as successive series of teeth 22 act on holes 24, I produce an increased tension on my strap 5 which in turn is held in any desired position of tension 25 by the action of latch 27 on teeth 22. In the event I have produced too great a tension I am able to release it by merely depressing latch release 29 and rotating roller 7 in the opposite direction until the desired amount of tension is obtained. This feature is especially important 30 since not only do individual horses vary a great deal in the amount of tension that is desired on belt 10, but after a period of riding, the same horse may require 35 loosening or tightening of the strap 10 which of course, may be easily effected in the manner described above while the rider is still in position in the saddle 2.

I have shown my device on the left hand side of the horse 1 but of course, it may be positioned on either side of the horse's body as desired, the same construction and principles of operation being employed.

I may fabricate my device out of any suitable materials. For example, my strap 5 may be leather but I may also use various plastic materials if desired. My housing 6 is usually made of metal which may be stainless steel or other metals, but it likewise is adapted for manufacture out of plastics as are all of the other component parts.

I am not limited to the type of wrench shown in FIG. 3A but may utilize any other type of wrench or key mechanism of conventional construction to effect rotation of my roller 7. When not in use, my wrench may be positioned in a saddle bag or other receptacle forming a part of the saddle equipment.

I claim:

1. A device for use in positioning a saddle on a horse comprising:
a housing positioned on one side of the body of said horse adjacent to said saddle;
a longitudinal strap, the first end of which is fixedly positioned on a first end of said housing and the second end of which is disposed for freely passing through a second end of said housing;
said strap being further disposed for passing through a saddle ring fixedly positioned on said saddle;
said strap being characterized by a plurality of holes therethru positioned along its length;
a roller positioned upon said housing in rotating relation therewith;
said roller being characterized by a plurality of protruding axial teeth disposed around its periphery;
said teeth being further disposed to engage said holes in said strap;
a hook fixedly positioned on said second end of said housing;
said hook being disposed for engagement with a cinch ring connecting to an underbelly strap on said horse;
means for rotating said roller thereby causing said teeth to cause movement of said strap,
whereby the distance between said saddle ring and said cinch ring may be varied and the pressure of said saddle and the tension of said underbelly strap on said horse may be adjusted simultaneously;
means positioned within said housing for engaging positively said teeth in a predetermined rotatative position whereby said roller is restricted from free movement;
means for disengaging said teeth from said rotative position to enable free movement of said roller.
2. The device of claim 1 including spring means positioned within said housing;
said spring means being disposed to engage said hook in said housing;
said spring means being further disposed to retain said cinch ring in positive engagement with said hook.
3. The device of claim 1 including:
a latch member positioned within said housing;
said latch member being disposed to engage said teeth in said roller in a given fixed position;
a release member positioned within said housing and disposed to disengage said latch member from said teeth.
